UNITED STATES PATENT OFFICE.

RÉGIS ROY, OF OTTAWA, ONTARIO, CANADA, ASSIGNOR OF ONE-FOURTH TO HENRY RITCHIE, OF OTTAWA, ONTARIO, CANADA.

ENVELOP.

1,210,699.

Specification of Letters Patent. Patented Jan. 2, 1917.

Application filed April 14, 1916. Serial No. 91,110.

To all whom it may concern:

Be it known that I, RÉGIS ROY, a subject of the King of Great Britain, and resident of the city of Ottawa, Province of Ontario, 5 Dominion of Canada, have invented certain new and useful Improvements in Envelops, of which the following is the specification.

This invention relates to improvements in envelopes particularly adapted to be used 10 with circulars, leaflets, pamphlets, catalogues, books and the like, and the objects of the invention are to dispense with sealing means of any usual form or metal clasps and strings, to permit of the contents of the 15 envelop being open to examination at all times, to prevent the contents from slipping out even with the roughest handling, and generally to adapt the envelop to better perform the functions required of it.

20 With the above and other objects in view the invention consists essentially of the improved construction particularly described and set forth in the following specification and accompanying drawings forming part 25 of the same.

In the drawings, Figure 1 is a perspective view of the improved envelop. Fig. 2 is a fragmentary longitudinal section of the open end of the envelop. Fig. 3 is a plan 30 view of an envelop blank showing one of the edges of the end folded and broken away to show the location of the flexible member therein.

Like characters of reference refer to like 35 parts in the several figures.

Referring to the drawing, A represents an envelop having the edges 10 of the opening 11 slit at each side and folded inwardly along the line 12 to embrace a flexible member 13 40 of string or light resilient wire therebetween, the portion of the envelop which is bent back being secured by mucilage or the like. Both edges are treated in this manner and are then folded inwardly within the 45 body of the envelop where they are secured by passing metallic clips 14 through the envelop adjacent to the longitudinal edges thereof, and in this way the opening 11 becomes restricted.

50 When this envelop is in use an article B is inserted therein and is prevented from slipping out by the rounded edges formed by the flexible member 13 embraced by the

ends 10 of the envelop. The article is retained in the envelop even against the 55 roughest usage and the envelop can be shaken without the contents becoming displaced. In withdrawing the article B from the envelop it is necessary to press the longitudinal edges of the envelop toward each 60 other so that the opening 11 will become extended whereupon the fingers may be inserted into the envelop and the contents B withdrawn.

As many changes could be made in the 65 above construction and many apparently widely different embodiments of my invention, within the scope of the claims, constructed without departing from the spirit or scope thereof, it is intended that all matter contained in the accompanying specification and drawings shall be interpreted as 70 illustrative and not in a limiting sense.

What I claim as my invention is:

1. An envelop of the class described having the ends of the open end slit along each side and bent inwardly, a member embraced between the folded portion of the ends and secured therein by mucilage, the ends being then bent inwardly into the body of the envelop, and means for securing the said ends in fixed position.

2. An envelop of the class described having the ends of its opening slit along each edge and bent inwardly, a strip of flexible 85 resilient material embraced by the bent portion of the edges and secured therein by mucilage, the ends being bent into the interior of the envelop, and means for securing the ends fixed within the envelop.

3. An envelop of the class described having the ends of its opening slit along each edge, the ends being bent inwardly, a strip of resilient material embraced by the bent portion of the edges and secured therein by 95 mucilage, the ends being bent into the interior of the envelop, and metallic clips for securing the bent portions of the edge in the interior of the envelop.

In witness whereof I have hereunto set 100 my hand in the presence of two witnesses.

RÉGIS ROY.
